UNITED STATES PATENT OFFICE.

ROBERT S. GRAHAM, OF NEW YORK, N. Y.

FILING DEVICE.

1,158,129.

Specification of Letters Patent.

Patented Oct. 26, 1915.

Application filed February 17, 1915. Serial No. 8,753.

To all whom it may concern:

Be it known that I, ROBERT S. GRAHAM, a citizen of the United States, residing at the city of New York, borough of Manhattan, county and State of New York, have 5 invented a certain new and useful Filing Device, of which the following is a specification.

This invention is a means for filing 10 memoranda or data so as to preserve the same for convenient future reference.

Persons engaged in literary and business pursuits, and more particularly travelers, often find occasion to jot down memoranda 15 of various kinds to be used for future reference, for which purpose it is customary to make notes on the backs of envelopes, business cards, or other scraps of paper. Such written memoranda often become mis- 20 placed or lost, and the writing thereon becomes more or less effaced by being carried in the pocket, so that on the whole a demand may be said to exist for an article convenient for writing the memoranda and for 25 filing the same for future reference, which article shall be so compact that it may be easily carried in the pocket and which shall be economical of manufacture.

The purpose of this invention is to pro- 30 vide an article possessing the characteristics above mentioned, and to this end it consists of a filing envelop composed of pliable fibrous material and a pad the leaves of which are attached to said envelop on the 35 outside thereof so as to be available for writing thereon, said leaves being smaller in size than the envelop so that they can be filed therein without folding them when torn off the pad and the flap of the envelop 40 being positioned so that it can be opened or closed without interference from the pad or the means for attaching the pad thereto.

In the drawings, Figure 1 is a perspective view of my filing device. Fig. 2 is a longitudinal section on the line 2—2 of Fig. 1. Fig. 3 is a plan looking at the rear of the article, the pad being shown in dotted lines.

A designates the envelop, the same being composed of fibrous or other material of a 50 flexible nature. Said envelop is closed at the ends, the front and one side edge, but the back of the envelop is open and provided with a flap a, the latter being adapted to be turned away from the back, as shown 55 in Fig. 1, so as to open said back for the easy introduction and removal of the memo-

randum pages. It is preferred to employ a heavy paper or a fabric in the manufacture of the envelop so that the article may be carried in the pocket for an indefinite 60 length of time without appreciable wear, particularly along the edges.

A pad B, composed of a desired number of leaves or pages, is positioned on the closed front side of the envelop, exteriorly 65 thereto so as to be easily accessible at all times for writing down a memorandum on the top page or leaf. The dimensions of the pad are less than those of the envelop, that is, the length and width of each page or 70 sheet is less than the interior dimensions of the envelop, so that the page can be torn off the pad and inserted into the envelop without requiring said page to be folded.

The pad and the envelop are fastened together rigidly near one end portion thereof, thus producing a unitary article wherein the pad sheets are inseparably attached to the envelop while the device is being carried, but obviously one or more of the written 75 sheets can be torn off the pad for filing the same within the envelop. As shown, the pad sheets and the envelop are fastened by staples C inserted through the pages or 80 sheets of the pad and through the envelop 85 near one end thereof, it being preferred to use two or more staples and to allow the other edges of the pad leaves to be free, but it is apparent that any suitable means may be used for uniting the pad and the 90 envelop.

My device is characterized by two structural features independent of the mere assemblage of a pad and an envelop, first, the attachment of the pad leaves or sheets 95 in a way to permit the flap a to be opened and closed without hindrance by the staples C, and second, the use of pad leaves or pages of a length less than the distance between the staples and the opposite end 100 portion of the envelop, whereby the leaf when detached may be easily introduced into the envelop without folding the same.

It is apparent that the article can be easily carried in the pocket owing to the 105 flexible materials employed in the envelop and the pad, so that said article is available for use instantly when required. The pad affords a most convenient means for writing down data, and the leaf can be at once torn off and filed away for safe keeping or for 110 future reference. The article supplies a

want in great demand by business people; and it is particularly well adapted for advertising purposes.

Having thus fully described the invention, what I claim as new and desire to secure by Letters Patent is:—

1. As a new article of manufacture, a pocket filing device comprising an envelop provided on the back thereof with a flap, 10 and a pad of memorandum leaves positioned on the front of the envelop, said pad and envelop being attached rigidly together near one end portion thereof so as to leave the flap on the back free and unconfined by the 15 fastening means.

2. As a new article of manufacture, a pocket filing device comprising an envelop closed on all sides except at the back and provided with a flap, a pad of memorandum 20 leaves positioned on the front of the en-

velop, and means for fastening an end portion of the pad to a corresponding end portion of the envelop, said attaching means being free from engagement with the flap and said memorandum leaves being of a 25 length less than the distance between the fastening means and the opposite end portion of the envelop, whereby the flap may be opened or closed at will and the memorandum leaves may be torn off the pad and filed in the envelop without folding said leaves and without hindrance from the attaching means.

In testimony whereof I have signed my name to this specification in the presence of 35 two subscribing witnesses.

ROBERT S. GRAHAM.
